UNITED STATES PATENT OFFICE

FREDERICK DUTSON MOSS, OF HORORATA, NEW ZEALAND.

HANDLE-FASTENING

1,081,546.

Specification of Letters Patent. Patented Dec. 16. 1913.

Application filed November 7, 1912. Serial No. 730,113.

To all whom it may concern:

Be it known that I, FREDERICK DUTSON Moss, a subject of the King of Great Britain, residing at Hororata, Canterbury, New Zealand, have invented a new and useful Handle-Fastening; and I do hereby declare the following to be a full, clear, and exact description of the same.

This invention relates to means that have been devised for use in securing to their handles slashers and other implements, having sockets to receive the handle ends. The means devised are intended to dispense with the necessity of passing a fastening rivet, or the like, through the socket and the portion of the handle therein, thereby weakening the handle so as to make it liable to break at such points.

The means for fastening the sockets embodied in this invention consist of a ring of metal that encircles the socket and is made of such a diameter as to jam on to the upper end of the socket when it is forced upward thereon, but to extend loosely around the lower end of the socket. Attached to the ring, at points diametrically opposite one another, are two metal straps each one of which is formed with an aperture near its end to receive a screw or like fastening.

In fixing the appliance the handle end is inserted in the socket in the usual way. The ring is then forced up the socket to cause it to closely encircle and grip the handle and the straps are then laid against the side of the handle above the socket top and fastened thereto by screws passing through them into the handle. These straps will therefore serve to keep the fastening ring at its upper position.

The invention is illustrated in the accompanying drawings, in which:

Figure 1 is a side elevation of the implement socket with the fastening means loose thereon. Fig. 2 is a top elevation thereof made fast upon a handle. Fig. 3 is a longitudinal section also showing the socket fastened to the handle.

A is the socket of the slasher or other implement which is made of any of the approved tapering shapes to receive a corre-

spondingly tapered end of the handle B. The socket is also preferably so made as to be capable of tightening upon the handle, for instance by forming it with the longitudinal slot or slots C extending forward from its back end.

D is the metal ring that encircles the socket and is made of such a diameter as to loosely encircle it when at the inner end of the socket but to jam thereon when moved along toward the outer end. This ring may be made of any approved cross sectional shape such as will provide for its sliding and gripping on to the socket when forced to its larger end.

E are the metal straps attached to the ring D. Two of these are shown arranged at points diametrically opposite one another. They are made of sufficient length to extend beyond the back end of the socket and are pierced with apertures F at their back ends to receive a screw or other fastening.

It will be seen that when a handle end is inserted into the socket, the ring being at the inner end thereof, and the ring is then forced out along the socket, it will cause the wall of the socket to tighten uniformly on to the handle and grip it firmly throughout the length of the socket. The ring is then prevented from giving back to loosen this grip, by fastening the straps E to the handle by means of screws or the like passed through the apertures F into the handle.

The handle end may be removed whenever required by unfastening the straps and forcing the ring forward to loosen its grip on the socket.

What I do claim as my invention and desire to secure by Letters Patent is:

1. The combination with a tool provided with a split handle receiving socket formed integrally with the tool; of means slidably mounted on the socket and permanently attached thereto and arranged to compress the split end of the socket when moved toward said end.

2. The combination with a tool provided with an integral tapering handle socket, said socket being provided with longitudi-

nal slits extending from the larger end; of a ring of less diameter than the tool body and larger end of the socket and slidable between the tool body and said larger end, 5 and means carried by the ring for securing the ring in adjusted position on a handle.

In testimony whereof, I have signed this

specification in the presence of two subscribing witnesses.

FREDERICK DUTSON MOSS.
